UNITED STATES PATENT OFFICE

133,955

DESIGN FOR A HURRICANE LAMP ADAPTER FOR CANDLESTICKS OR SIMILAR ARTICLE

Carl J. Uhrmann, Bellaire, Ohio, assignor to Imperial Glass Corporation, Bellaire, Ohio, a corporation of Ohio

Application May 28, 1942, Serial No. 107,029

Term of patent 14 years

To all whom it may concern:

Be it known that I, Carl J. Uhrmann, a citizen of the United States of America and resident of Bellaire, county of Belmont, and State of Ohio, have invented a new, original, and ornamental Design for a Hurricane Lamp Adapter for Candlesticks or Similar Article, of which the following is a specification, reference being had to the accompanying drawing, forming part thereof, in which—

Figure 1 is a side elevational view, partially in section, of a hurricane lamp adapter for candlesticks or similar article, showing my new design; and

Figure 2 is a top plan view of the same.

I claim:

The ornamental design for a hurricane lamp adapter for candlesticks or similar article, substantially as shown.

CARL J. UHRMANN.
